MASK STRUCTURE

James Edward Duggan, New Brighton, Pa.

Application September 8, 1942, Serial No. 457,658

7 Claims. (Cl. 91—65)

This invention relates generally to mask structures for protecting one portion of a given surface from paint or the like applied to another portion thereof, and refers more particularly to mask structures of the type mentioned that are applicable to and adapted to protect surfaces having odd or irregular contours, beaded surfaces, or corrugated, roughened or uneven surfaces that heretofore were difficult or impossible to mask satisfactorily. The invention contemplates also the provision of a mask structure applicable to airplane fuselages, wings and control elements, as well as vehicle bodies, boats and military vehicles such as tanks, trucks, tractors and the like.

In fact, any given surface, whether smooth or otherwise, may be masked by my improved structure.

One of the essential objects of my invention is to provide a mask structure wherein the masking element thereof has suitable yieldable means to compensate for and fit snugly against irregular or uneven surfaces to be protected.

Another object is to provide a mask structure wherein the attaching means thereof has a yieldable connection with the masking element to compensate also for irregular or uneven surfaces to which the structure may be applied.

Another object is to provide a mask structure that may be easily and quickly applied to the surface to be protected, that will effectively mask such structure, and that may be easily and quickly removed without marring the surface with which it is engaged.

Another object is to provide a mask structure that will stand repeated handling and use and is serviceable whenever needed. No adhesive tape or similar material of any kind is needed, hence none is scrapped or wasted as heretofore.

Other objects, advantages and novel details of construction of this invention will be made more apparent as this description proceeds, especially when considered in connection with the accompanying drawing, wherein:

Figure 1 is a fragmentary perspective view of a mask structure applied to a given surface to be protected;

Figure 2 is a fragmentary perspective view of the mask structure with parts broken away and in section;

Figure 3 is a vertical sectional view through one of the suction cups;

Figure 4 is a top perspective view of a slight modification;

Figure 5 is a bottom perspective view of the structure illustrated in Figure 4.

Referring now to the drawing, A is a masking element, and B are attaching elements of a mask structure embodying my invention.

As shown, the masking element A is a laminated structure and has a relatively thick lower layer 10 for engagement with the work and a relatively thin backing sheet 11. The layer 10 and backing sheet 11 may be secured together in surface to surface relation by any suitable means, such, for example, by an adhesive substance, cement or bonding agent, and may be any shape or configuration desired.

15 Preferably the layer 10 is formed of rubber, rubber composition, felt or felted fibrous material or any other flexible and yieldable material that is soft enough to obtain the desired masking operation. The rubber used may be natural, synthetic, reclaimed or sponge, or any combination thereof, as desired. The backing sheet 11 may be formed of sheet metal or any other sheet material of sufficient strength to form a backing or reinforcement to which the layer 10 may be

20 adhered. If desired, such backing sheet may be relatively stiff and rigid or may be flexible and pliable, but in either instance is relatively thin.

25 In the present instance, the laminated structure forming the masking element A is provided at spaced points thereof, preferably adjacent the corners, with openings 12 for the reception of the attaching elements B. Preferably the walls of these openings are stepped as illustrated in Figure 2 by having the openings 13 in the backing sheet 11 smaller than the openings 14 in the lower layer 10, however this arrangement may be varied as desired.

30 In the present instance, the laminated structure forming the masking element A is provided at spaced points thereof, preferably adjacent the corners, with openings 12 for the reception of the attaching elements B. Preferably the walls of these openings are stepped as illustrated in Figure 2 by having the openings 13 in the backing sheet 11 smaller than the openings 14 in the lower layer 10, however this arrangement may be varied as desired.

35 The attaching elements B are loose in the openings 12 and preferably have suction cup portions 15 for engagement with the surface to which the mask structure is to be applied, and spring arms 16 and 17, respectively, that extend radially from the stem 18 of the suction cup portions 15 and bear upon the backing sheet 11 of the masking element.

40 Preferably the suction cup portions 15 correspond to the suction cup structures embodied in my application filed March 23, 1942, bearing Serial No. 435,890. More specifically, each suction cup portion 15 is formed of resilient material such as rubber or rubber composition and has a concavo-convex body 20 provided at the center thereof with the stem 18. Within the body 20 at one side of the stem 18 is a spherical hole 21,

45 while at diametrically opposite sides of said hole

are aligned cylindrical openings 22 and 23. The opening 22 is relatively small and extends inwardly from the hole 21 to the concave suction face 24 of the body 20, while the opening 23 is larger and extends outwardly from the hole 21 to the convex face 25 of the body. Located within in the hole 21 and opening 23 in the body are spherical and stem portions 26 and 27, respectively, of a metal valve element 28 for controlling the flow of air through the smaller inwardly extending opening 22. Preferably this valve element 28 is provided at its outer end with a knob or finger piece 29 by which it may be manipulated and has a longitudinally extending passage 30 and branch passages 31 and 32, respectively, for air. As shown, the longitudinally extending passage 30 extends inwardly from the outer end of the valve element to a point substantially at the center of the spherical portion 26, while the branch passages 31 and 32 extend from the inner end of said longitudinally extending passage 30 to and are normally closed by the walls of the hole 21 upon opposite sides of the inwardly extending opening 22.

Preferably the spring arms 16 and 17 are alike and are integral parts of a leaf spring 40 that is provided substantially mid-way its ends with a suitable slot 41 for the stem 18 and has a length in excess of the diameter of the openings 12. To obtain the desired results, such arms 16 and 17 have arched portions 43 and 44 that extend over the edges of the openings 12 and have open return bent end portions 45 and 46 that seat upon the backing plate 11.

Thus, when it is desired to protect one part, including the corrugated portion 50, of a given surface 51, from paint being applied to another part thereof, the masking element A may be applied to the part to be protected as illustrated in Figure 1 so that the lower engaging surface of the soft and yieldable lower layer 10 thereof will conform to the contour of and completely cover or mask the part, including the corrugated portion, of the surface to be protected. The attaching elements B will hold the masking element A in the applied masking position. This may be accomplished by simply pressing the stems 18 of the respective suction cup portions 15 inwardly relative to the openings 12 in the masking element to cause the suction faces 24 of such suction cup portions to create a vacuum and properly adhere to the surface 51. When this is done, then the spring arms 16 and 17 will be compressed to yieldably press and hold the masking element A firmly against the part of said surface to be protected. If desired, the stem 18 of each suction cup portion 15 may be separate from and threadedly engaged with the body 20 so as to be adjustable to vary the tension on the spring arms 16 and 17.

When it is desired to remove the masking element A from the masking position mentioned, the valve elements 28 of the suction cup portions may be pulled outwardly a slight amount to cause the resilient walls of the holes 21 in the respective concavo-convex bodies substantially to be distorted or deformed sufficiently by the spherical portions 26 of the valve elements to allow the branch passages 31 and 32 in such valve elements to be uncovered and thereby permit air from the atmosphere to flow through the passages in the valve elements and the inwardly extending openings 22 in the bodies 20 to the suction faces 24 to break or destroy the vacuum between such faces and the surface 51 engaged

thereby. The mask structure as a unit may then be bodily removed for subsequent engagement with another part of the same surface or with another surface, as desired.

5 In Figures 4 and 5 I have illustrated a slight modification wherein the masking element A' has only strips 60 of soft material as aforesaid at the margins or edges of the underside of the backing sheet 11^a. Preferably such strips 60 are spaced apart or broken away adjacent the corners of the backing sheet 11^a as illustrated in Figure 5 but may, if desired, be continuous and uninterrupted. Also in this construction the backing sheet 11^a may be provided at approximately the center thereof with an opening 61 representing a letter of the alphabet, a numeral or other design or configuration and may be provided at the edges of such opening with continuous strips 62 of soft material as previously described. Such strips 62 would, of course, be substantially equal in depth to the strips 60 at the edges of the backing sheet 11^a. Moreover, other stripped openings may be provided in the backing sheet 11^a within the area thereof bounded by the strips 60 instead of or in addition to the one stripped opening 61, as desired. Attaching elements B', corresponding to the attaching elements B, would be used in suitable openings 12^a in the backing sheet 11^a to hold the masking element A' in proper masking position.

What I claim as my invention is:

1. A mask structure of the class described comprising a plate-like masking element for covering a surface to be protected, and means for holding said element in operative masking position relative to said surface, the plate-like element being provided upon the underside thereof with cushioning means for yieldably supporting the element upon said surface, said means being formed of resilient material so as to conform to and fit snugly against any uneven portion of said surface, the holding means being loose with respect to said element and including suction means beneath said element for engagement with said surface, and spring arms upon said element and operatively connected to said suction means.

2. A mask structure of the class described comprising a plate-like masking element for covering a surface to be protected, and means for holding said element in operative masking position relative to said surface, the plate-like element having holes therein at spaced points thereof and provided upon its underside with cushioning means for yieldably supporting the element upon said surface, said means being spaced from the holes in said element whereby said holes are uncovered, and formed of resilient material so as to conform to and fit snugly against any uneven portion of said surface, the holding means being loose within said holes and including suction means beneath said element for engagement with said surface, and arched spring arms terminally seated upon said element and operatively connected to said suction means.

3. A mask structure of the class described comprising a laminated plate-like masking element for covering a surface to be protected, and means for holding said element in operative masking position relative to said surface, the lowermost ply of said laminated element being formed of resilient material for yieldably supporting said element upon said surface and for conforming to and fitting snugly against any uneven portion of said surface, the uppermost ply of said lam-

inated element being a backing plate, said plies having registering openings therein, the holding means extending freely through said registering openings and including suction means within the opening in the lowermost ply engageable with said surface, and arched spring arms having open return bent portions terminally seated upon the top of the uppermost ply adjacent the edges of the openings therein.

4. A mask structure of the class described comprising a plate-like masking element for covering a surface to be protected, and means for holding said element in operative masking position relative to said surface, the plate-like element having holes therein at spaced points thereof and provided upon its underside with resilient cushioning means for yieldably supporting the element upon said surface, said cushioning means being spaced from the holes in said element whereby said holes are uncovered, the holding means being loose with respect to said element and having an upstanding portion extending freely through said holes, said holding means including suction means beneath said element and engageable with said surface, and spring means spanning said holes and terminally seated upon the upperside of said element at substantially diametrically opposite points of said holes, said spring means being connected intermediate its ends to the upstanding portion aforesaid of said holding means.

5. A mask structure of the class described comprising a plate-like masking element for covering a surface to be protected, and means for holding said element in operative masking position relative to said surface, the plate-like element having holes therein at spaced points thereof and provided upon its underside with cushioning means for yieldably supporting the element upon said surface, said cushioning means being spaced from the holes in said element whereby said holes are uncovered, the holding means being loose with respect to said element and having a portion free within said holes, said holding means including suction means beneath said element and engageable with said surface, and spring means spanning said holes and terminally

seated upon the upperside of said element, said spring means being connected to the portion aforesaid of said holding means disposed within said holes.

5. A mask structure of the class described comprising a laminated plate-like masking element for covering a surface to be protected, and means for holding said element in operative masking position relative to said surface, the lowermost ply of said laminated element being formed of resilient material for yieldably supporting said element upon said surface and for conforming to and fitting snugly against any uneven portion of said surface, the uppermost ply of said laminated element being a backing plate, said plies having registering openings therein, the holding means being loose with respect to said element and having an upright portion extending freely through and movable within said registering openings, 10 said holding means including suction means movable freely within the opening in the lowermost ply and engageable with said surface, and spring means seated on top of said laminated element and having a part connected to said upright portion.

7. A mask structure of the class described comprising a laminated plate-like masking element for covering a surface to be protected, and means for holding said element in operative masking position relative to said surface, the lowermost ply of said laminated element being formed of resilient material for yieldably supporting said element upon said surface and for conforming to and fitting snugly against any uneven portion of said surface, the uppermost ply of said laminated element being a backing plate, said plies having registering openings therein, the holding means being loose with respect to said element and having a portion extending freely through and movable within said registering openings, 30 said holding means including suction means movable freely within the opening within the lowermost ply and engageable with said surface, and spring means upon the uppermost ply of said laminated element and connected to the portion aforesaid of the holding means.

JAMES EDWARD DUGGAN.
